(57) **CLAIM**

The ornamental design for the top cap for an electronic cigarette, as shown and described.

DESCRIPTION

FIG. 1 is a front view of the top cap for the electronic cigarette showing our new design, the left side, right side, and rear views are identical;

FIG. 2 is a top view thereof;

FIG. 3 is a bottom view thereof; and,

FIG. 4 is a front view thereof, showing the top cap for an electronic cigarette in a state of use, for clarity of disclosure, coupled to the body of an electronic cigarette.

The broken lines in FIG. 4 depict the body of an electronic cigarette that forms no part of the claimed design.
